US00D620804S

(12) **United States Design Patent**
Bogert et al.

(10) **Patent No.:** **US D620,804 S**
(45) **Date of Patent:** **** Aug. 3, 2010**

(54) **FRAGRANCE BOTTLE AND CAP**

(75) Inventors: **Elizabeth Bogert**, Croton on Hudson, NY (US); **Lance Colin McGregor**, Brooklyn, NY (US); **Jin Chung**, New York, NY (US)

(73) Assignee: **Christian Casey LLC**, New York, NY (US)

(**) Term: **14 Years**

(21) Appl. No.: **29/352,079**

(22) Filed: **Dec. 16, 2009**

(51) **LOC (9) Cl.** **09-01**

(52) **U.S. Cl.** **D9/544**; D9/439; D9/559;
D9/573

(58) **Field of Classification Search** **D9/434, D9/435, 439, 516, 520, 529, 544, 546, 559, D9/560, 566, 568, 573, 574, 682, 686, 687, D9/694; 215/381-385; 220/660, 662, 665**

See application file for complete search history.

(57) **CLAIM**

The ornamental design for a fragrance bottle and cap, substantially as shown and described.

DESCRIPTION

FIG. 1 is a top, front and right side perspective view of a fragrance bottle and cap showing our new design;

FIG. 2 is a top plan view thereof;

FIG. 3 is a front elevation view thereof, the rear elevation view being a mirror image thereof;

FIG. 4 is a side elevation view thereof, the opposite side elevation view being a mirror image thereof; and,

FIG. 5 is a bottom plan view thereof.
